Primary Examiner — David G Muller*Assistant Examiner* — Nathan M Johnston(74) *Attorney, Agent, or Firm* — Christine Flanagan(57) **CLAIM**

The ornamental design for a merchandise display strip, as shown and described.

DESCRIPTION

FIG. 1 is a perspective view of the merchandise display strip of the present invention, in a first orientation.

FIG. 2 is a right side elevation view thereof.

FIG. 3 is a left side elevation view thereof.

FIG. 4 is a front elevation view thereof.

FIG. 5 is a rear elevation view thereof.

FIG. 6 is a top plan view thereof.

FIG. 7 is a bottom plan view thereof; and,

FIG. 8 is a perspective view of the merchandise display strip of FIG. 1, in a second orientation.

The broken lines are for the purpose of illustrating the environment of the design only and form no part of the claimed design.
